UNITED STATES PATENT OFFICE

EDOUARD JOSEPH PETER, OF VILLEMOMBLE, FRANCE

ARRANGEMENT FOR INCREASING THE EFFICIENCY OF LIFTING, TRACTION, AND PROPULSION MEANS

Application filed July 6, 1928, Serial No. 290,862, and in Switzerland July 7, 1927.

The present invention, of divine inspiration, relates to an improved arrangement adapted to increase the efficiency of the elements employed for lifting, traction, propulsion and steering, such as the planes or wings of aircrafts and aerial propellers in general.

The arrangement according to the invention is characterized by the fact that at least two planes or wings or propeller blades, are superposed according to a stepped disposition and are horizontally spaced apart, so that the fluid which enters below each plane, wing or propeller blade, will be projected and compressed perpendicularly to the latter and in the rear of the preceding element, with reference to the direction of travel of said elements.

My said improvement is of a general order, and is applicable to propellers for traction or propulsion which act upon the air or the water or are acted upon by the same, and also to inclined planes which are moving forward or rotating, or in which these movements are combined, as well as the rudders.

In the appended drawing given only by way of example:

The figure shows a sectional view of an arrangement of aerofoils according to the invention.

The pressures upon the lower face of a plane to which a motion of translation is imparted are greater near the leading edge, then diminish at a rapid rate and then diminish gradually, and finally become zero at the rear edge.

To take advantage of this principle, let it be assumed that a wing plane is decomposed by sectioning it in the lengthwise direction, thus forming several elements $P_1-P_2-P_3-P_4$ —which are superposed in the vertical direction and which, when projected in the horizontal plane, are spaced apart as shown in the drawing.

The current of air A meets the lower face of the plane P and is projected perpendicularly at the point of contact, against the lower air current A_i , thus producing a compression which forces out the two air currents, the first downwardly and the second according to an upward curve in the rear of the plane P.

The air current A_1 is projected by the plane P_1 against the rising air current A which impels the air current A_2 , thus producing a compression below the plane P_1 and in the rear of the preceding plane which occupies a lower position; this compression is stronger than the one caused by the plane P and it forces the opposite air currents upwardly and downwardly as in the preceding case.

The same action is repeated with each of the succeeding planes, and this principle characterizes the carrying feathers of the wings of the large birds which are able to carry prey whose weight exceeds their own.

By the said arrangement of multiple planes I am able to obtain an accumulation of maximum pressures which is a multiple of the yield offered by a single plane having an equal surface. When the apparatus or aeroplane is losing speed, it will be more readily righted, the air being allowed to pass between the planes. When starting in flight, or landing, the acquired speed of the apparatus will be less affected by a gust of wind striking the top of the wings in a direction which is oblique to the line of flight.

In addition to a very strong and simple construction, the said apparatus will afford a wide range of sight and will provide for the maximum range of speeds while offering an approved safety and stability.

The said planes or wings, independently of their shape, may or not be connected together by struts, ribs or ties, and the propeller blades may be joined together or not at or near the ends. Similarly the set of planes, wings, or propeller blades, or the like, may be constituted by a first or main portion in one piece and by a number of planes, wings or blades attached to or integral with said main portion and having an offset relative disposition in the vertical and horizontal directions, as above set forth.

Obviously, the invention as herein specified may be employed with all classes of aircraft, without departing from the spirit of the invention.

Having now described my invention, what I claim as new and desire to secure by Letters Patent is:

In an aircraft, a wing embodying a plurality of elements, the chord of each element is but a small fraction of the total chord of the wing, said elements being disposed in a 5 negative staggered relation of 45° from the forward element towards the rear and successively horizontally spaced apart at substantially one chord interval.

In testimony whereof I have signed my
10 name to this specification.

EDOUARD JOSEPH PETER.
